UNITED STATES PATENT OFFICE.

FREDRICK R. WILCOX, OF STAR LIME WORKS, KENTUCKY.

STEEL FENCEPOST.

Application filed May 26, 1926. Serial No. 111,789.

This invention aims to provide a post so constructed that it will take up the slack in wire and hold the wire tightly.

It is within the province of the disclosure 5 to improve generally and to enhance the utility of devices of that type to which the invention appertains.

With the above and other objects in view which will appear as the description 10 proceeds the invention resides in the combination and arrangement of parts and in the details of construction hereinafter described and claimed, it being understood that changes in the precise embodiment of the 15 invention herein disclosed, may be made within the scope of what is claimed, without departing from the spirit of the invention.

In the drawings:—

- 20 Figure 1 is an elevation;
Figure 2 is a longitudinal section;
Figure 3 is a top plan;
Figure 4 is a vertical section showing a modification;
25 Figure 5 is a vertical section showing another modification.

The post forming the subject matter of this application includes a main member 1 which is of arcuate or trough-shape, the 30 lower end of the main member 1 being embedded in the ground 2 or being mounted in any other suitable manner. The post includes an auxiliary member 3 which is arcuate or trough-shaped. The auxiliary member 3 is somewhat shorter than the main member 1 and is of the same cross section as the main member 1, so that the members 1 and 3 can be cut off from the same piece of stock. The members 1 and 3 are held together 35 by clamps of any desired construction, such as U-bolts 4, the arms of which pass through yoke bars 5, the ends of the arms of the U-bolts 4 carry nuts 6 which engage the yoke bars. The yoke bars 5 rest against the 40 forward edges of the main member 1, whereas the convexity of the auxiliary member 3 is received in the bends of the U-bolts. The body of the fence is marked by the numeral 7 and, for simplicity in illustration, has been 45 shown as consisting merely of a few wires. It will be understood, however, that the device claimed is adapted to hold a netting fence, or any other kind of a flexible fence.

If desired, a rail 8 may be held on the main member 1 by means of a U-bolt 9, the arms of 55 which pass through yoke bars 10 engaging the forward surface of the rail 8, nuts 11 being threaded on the arms of the U-bolt 9, the nuts engaging the yoke 10. Referring to Figure 2 particularly, it will be observed 60 that the U-bolt 9 serves to support the auxiliary member 3 of the fence post. The rail 8, the U-bolt 9, the yoke 10 and the nuts 11 may be omitted if desired.

The fence body 7, whatever its form may 65 be, is extended along the convexed surface of the main member 1 of the post, and when the auxiliary member 3 is drawn up against the main member 1, as in Figure 3, by the action of the U-bolts 4, the edges of the 70 auxiliary member 3 will flex the fence body 7 across the main member 1, as clearly shown in Figure 3, thereby tightening up the fence body and at the same time gripping it 75 securely.

In Figure 4, parts hereinbefore described, have been designated by numerals previously used, with the suffix "a". The main member 1^a is likely to give away at a point 15 adjacent to the surface of the 80 ground 2^a, and then recourse is had to an extension 16 fitted on the lower end of the main member 1^a and held thereon by a bolt 9^a, the upper end of the extension 16 abutting against the lower end of the auxiliary 85 member 3^a, and the extension being embedded in the ground.

In the form shown in Figure 5, parts hereinbefore described, have been designated by numerals previously used, with the suffix "b". 90 In this form of the invention, recourse is had to a brace which is denoted generally by the numerals 17, the brace comprising a horizontal body 18 equipped at one end with a depending foot 19 embedded in the ground 95 2^b, and supplied at its other end with an upstanding arm 20 abutting against the auxiliary member 3^b and held on the main member 1^b by means of the U-bolt 9^b.

What is claimed is:—

1. In a device of the class described, a main member and an auxiliary member of identical cross section, and each of arcuate cross section, the edges of the auxiliary member cooperating with the convexed surface of the main member to flex and grip the 100 105 fence, or any other kind of a flexible fence.

fence body, and clamping means uniting the main and auxiliary member.

2. A device of the class described, constructed as set forth in claim 1, and further characterized by the fact that the clamping means consists of a U-bolt surrounding the auxiliary member, a yoke bar

adjacent the edges of the main member, and nuts on the U-bolt and engaging the yoke bar.

In testimony that I claim the foregoing as my own, I have hereto affixed my signature.

FREDRICK R. WILCOX.
